APPARATUS FOR HEAT INTERCHANGE

Hans Holzwarth, Dusseldorf, Germany, assignor
to The Holzwarth Gas Turbine Company, San
Francisco, Calif., a corporation of Delaware

Application April 20, 1931, Serial No. 531,266
In Germany April 23, 1930

4 Claims. (Cl. 257—247)

My invention relates to heat exchangers and has for its object to provide a novel and improved apparatus for effecting heat interchange between two fluids.

- 5 The present invention proceeds from the observation that the processes and devices heretofore employed for transferring heat from substances of poor conductivity, as for example highly heated oil, to substances of better heat conductivity, as for example water, are entirely incapable of attaining sufficiently high rates of heat transmission. Thus for example, in the investigations of Heinrich Stueckle (Forschungsheft 271), the coefficient of heat transfer from oil 10 through the wall of a tube to water at oil velocities between 0 and 1 meter per second is given as 50 to a maximum of 300 cal./m²/hr./° C. (large or kilogram calories per square meter of heat transfer surface per hour per degree centigrade). 15 20 A heat exchanger designed upon the basis of such coefficients of heat transfer would be extremely bulky and cumbersome and would consequently offer large cooling surfaces from which heat would be lost to the atmosphere, so that an apparatus of this kind is not only expensive, but unsatisfactory from the standpoint of heat economy.

The present invention makes possible a surprising increase in the rate of heat transfer beyond values of about 1600 cal./m²/hr./° C., and 30 accomplishes such result by conducting the substance of poor heat conductivity along the heat transferring wall in the form of a thin film and with an average velocity of at least 1.3m/sec. The film may be produced in various ways; for example, the tubes traversed by the material of poor heat conductivity are provided with cores of such external diameter that there is left only a narrow annular space, through which such substance flows in the form of a hollow cylindrical film; the 35 tubes being at the same time contacted along their outer surfaces by the substance of better heat conductivity. These annular spaces may be created also by placing two concentric tubes one within the other and causing the better heat conducting substance to flow through the interior of the inner tube. The first-mentioned form of the invention has the advantage of much greater simplicity. The annular intermediate space can be subdivided in the manner of a helix. The ribs 40 45 50 or other devices which produce the helical subdivision of the intermediate space between the inner wall of the tube and the core insert may advantageously be formed or positioned between suitable notches or depressions in the inner wall 55 of the tube. The ribs may also be arranged upon

the core itself; researches have shown, however, that the formation of the ribs upon the inner wall of the tubes is more advantageous from the standpoint of heat transfer. The tubes may be given any known special construction upon the sides 60 contacted by the better heat conducting material for improving the heat transfer; for example, they may be provided with projections or ribs or similar devices for increasing the heat transfer surfaces. 65

On the accompanying drawings is shown a graph (Fig. 1) on which the coordinates are divided logarithmically, the ordinates representing the rates of heat transfer obtained according to the invention, expressed in cal./m²/hr./° C., 70 while the abscissæ represent the average oil velocities in meters per second. The curves represent the results of experiments made with a hollow cylindrical film. With the curve 1a the average oil temperature was 140° C.; with the curve 1b, 160° C.; with the curve 1c, 180° C.; with the curve 1d, 200° C.; with the curve 1e, 225° C.; and with the curve 1f, 250° C. The curves show that at oil velocities slightly above 1.3m/sec. a point of instability appears, beyond which a rapid increase in the heat coefficients is to be observed. 80

In accordance with the present invention, therefore, oil velocities above 1.3m/sec. are employed together with the feature that the material of poor heat conductivity is conducted along the 85 heat transferring wall in the form of a thin film, so that the rate of heat transfer can be raised from 4 to about 32 times the value heretofore attainable; the heat transfer surfaces can therefore be reduced to a corresponding extent as compared with the surface areas heretofore required. 90

If high boiling oils serve as the material of poor heat conductivity, there arises the unfavorable circumstance that the oil, when the apparatus 95 is not in operation, forms a viscous layer in the narrow spaces available for film formation, which layer cannot be completely removed even by the use of high pressures. In a further development of the invention, certain of the tubes in the heat exchanger are not filled with cores but have their whole interior free for the passage of oil. As soon as the plant is started, these tubes are immediately traversed by the highly heated oil and effect the transfer of heat to the substance of 100 better heat conductivity, such as water. The water becomes heated and in turn heats the thickened oil films which clog the annular spaces in the tubes provided with cores. Under the influence of the heating, the viscosity of the oil 105 110

layer is reduced so that the flow of oil through cored tubes takes place. The tubes not provided with cores are preferably closed at this instant against the entry of oil, by either manually or 5 automatically (e. g. thermostatically) operated devices, so that from this moment on, the heat exchange takes place under the favorable conditions provided by the present invention.

The heat exchangers to be employed in carrying out my improved process may be constructed in various ways. A particularly simple construction results when the tubes provided with core inserts are arranged between two collector chambers or headers for the uncooled and the cooled 10 substance of poor heat conductivity, in the manner of the heating tubes of a tubular boiler. Upon removal of the covers of the collector chambers, the core inserts can be comparatively easily removed from the heating tubes connecting such 15 chambers, so that the tubes can be readily cleaned. The tubes with the core inserts can, however, be connected to collecting chambers, so as to project laterally therefrom in the manner of a cantilever, in which the inserts are provided with bores communicating with such chambers and serving to 20 conduct the substance of poor heat conductivity in one direction to the far end of the tube where the oil reverses in direction and flows through the annular spaces. If these bores are connected 25 with the collecting chambers for the uncooled substance of poor heat conductivity, the advantage is obtained that when a plant is set into operation with the use of oil as the heat carrier, the uncooled hot oil first flows into the hollow 30 spaces in the inserts and thus heats up the viscous oil films clogging the annular spaces about such inserts. In such an arrangement it becomes unnecessary to provide special starting tubes without inserts. The tubes with the core inserts can 35 be arranged at both sides of the collecting chambers for the uncooled and the cooled substance of poor heat conductivity, so that by displacing the tubes of adjoining chambers it is possible to 40 combine the tubes into groups and to dispose 45 a number of groups, one behind the other, along the length of the heat exchanger.

Heat exchangers built in accordance with the present invention are of particular utility for the transfer to water of the heat abstracted by 50 cooling oil from combustion engines, particularly combustion turbines. In the cooling of combustion turbines, the most diverse conditions must be maintained. First of all, the cooling may be driven only to such a degree that, on the one hand, 55 the structural materials are still protected against excessive temperatures, while on the other hand, the efficiency of the power plant is not impaired by an unnecessarily large abstraction of heat. In particular, the cooling process must be so determined 60 that the heat transferred to the cooling medium can be utilized as completely and as efficiently as possible in the operation of the combustion turbine plant. If, for example, as already proposed, water is employed as the cooling medium, a definite maximum temperature may not 65 be exceeded if the formation of steam is to be avoided with certainty; or else the cooling water must be placed under pressure to avoid the formation of steam. Cooling with liquid water with 70 the maintenance of a definite maximum temperature is prejudicial to the over-all efficiency of the plant because the withdrawn heat cannot be utilized efficiently; placing the water under pressure has the disadvantage that the cooling jackets 75 must be made pressure proof. To avoid these

disadvantages, it has already been proposed to employ high boiling cooling media, as for example high boiling oil as the cooling agent in piston combustion engines. If, however, the cooling oil temperature were permitted to rise sufficiently high in such piston engines to make possible the generation of steam of an economical pressure, the cylinder wall temperatures would rise so high as to make proper lubrication of the piston exceedingly difficult, if not entirely impossible. This limitation does not exist in combustion turbines because the parts to be cooled, as for example the walls of the explosion chambers, the nozzles, the nozzle ring and the rotor housing, neither move nor are in contact with moving parts, so that the matter of slidably guiding other machine parts within one of the cooled parts need not be taken into consideration at all. In addition, a special advantage occurs in combustion turbines operating with intermittent regulation in which individual explosion chambers are set into or cut out of operation to increase or decrease the output of the plant. The carrying out of this method of control requires that as soon as idle explosion chambers are cut in they must immediately assume normal operating conditions in order that the degree of non-uniformity of the machine may remain within permissible limits. If the idle explosion chambers were permitted to become cold while they were not in operation, the regulation 100 of the plant would be subject to serious difficulties. Because of the fact that the idle explosion chambers are constantly traversed by the hot cooling oil stream, they remain at a temperature which makes immediate starting of such explosion chambers possible. 110

In addition to securing these advantages as contrasted with the known modes of cooling, my novel cooling process for combustion turbines is distinguished over prior processes also by the 115 fact that the heated cooling oil for absorbing the heat of the parts to be cooled is conducted past water-cooled walls in the forms of a thin film and with an average velocity of at least 1.3 m/sec., and the generated steam then introduced in the heat economy of the combustion turbine, as by being charged into a gas turbine to assist in keeping the blades and other parts thereof cool, or into a steam turbine forming part of the power plant. If for example, the oil is introduced into the combustion turbine at a temperature of 230° C., or if the recooling of the heated oil is made to take place only down to this temperature, and a temperature rise of about 35° is permitted in the cooling jackets, the heated oil 130 is in a condition to generate steam in the heat exchanger of an economical, useful pressure of about 20 atmospheres. This steam pressure is obtained without the necessity of making the cooling jackets of the combustion turbine proof 135 against this high pressure. The cooling oil temperature itself can be raised, without the limitations present in piston combustion engine operation, to such a height as is necessary for the production of steam of an economical pressure. 140 My improved cooling process thus affords, by the use of intermittent regulation, the particular advantage that the temperature conditions in all of the cooling chambers are maintained uniform in spite of the cutting out of certain of the 145 explosion chambers.

Steam generators constructed according to the present invention offer particular advantages in combustion engine power plants, especially constant volume explosion turbine plants for ve- 150

hicles, preferably locomotives, such as described in my copending application Serial No. 512,340, because the space requirement of my improved heat exchangers is so small that they may be positioned, for example, upon the roof of the vehicle and thus do not interfere with the machine structures themselves, and enable the prescribed profile for the locomotive to be maintained.

10 The accompanying drawings illustrate by way of example two embodiments of the invention; in said drawings,

Fig. 1 presents a graph showing the relationship between the rate of heat transfer and the 15 average velocity of the oil;

Fig. 2 is a vertical longitudinal section of a heat exchanger built in accordance with the present invention;

Figs. 3 and 4 are transverse sections along the 20 lines III—III and IV—IV of Fig. 2;

Fig. 5 illustrates a second embodiment of the invention;

Fig. 6 shows on an enlarged scale a longitudinal section through the groups of connections of ad- 25 joining collecting chambers; and

Figs. 7, 8 and 9 are transverse vertical sections along the lines VII—VII, VIII—VIII and IX—IX respectively, of Fig. 5.

The numeral 5 designates the boiler in which 30 the heat of the cooling oil is transferred to liquid, preferably preheated water to generate steam therefrom. The feed water flows through conduit 6 first into the distributing space 7 and from the latter it is introduced into the boiler space 35 through the distributing tubes 8 and 9 which extend along the length of the boiler. Groups of tubes 10 connect the collecting chambers or headers 11 and 12 for the uncooled or cooled oil in the manner of the heating tubes of tubular 40 boilers. The oil is drawn into or out of the headers 11 and 12 by pipe sections 13 and 14. According to the invention, the individual tubes 10 of the group of heating tubes are filled by means of cores 15 which leave intervening annular spaces 45 of such radial depth as to form the oil streams flowing through the tubes into thin unbroken cylindrical films. The cores 15 are centered in the tubes 10 in any suitable manner (not shown); for this purpose, centering ribs may, for example, 50 be provided on the inner surfaces of the tubes, or the ends of the tubes may be provided with bushings which support the ends of the inserts.

As is shown in Fig. 3, separate tubes 16 are 55 provided which have no core inserts and serve for starting the apparatus. On starting, when the congealed or highly viscous oil films in the cored tubes move very sluggishly or not at all, the tubes 16 are traversed by the heating oil without difficulty as they oppose less resistance 60 to the latter so that the body of water in the boiler 5 becomes heated and in turn heats the congealed oil films located in the annular spaces between the cores 15 and the inner walls of the heating tubes 10 and thereby reduces the 65 viscosity of such oil films. After a short time, the viscosity of the oil films is reduced to such an extent that they begin to flow rapidly and thus the conditions for oil film formation according to the invention are fulfilled. At about 70 this instant, the tubes 16 are closed by any suitable devices, as by means of plugs 16a located within one of the headers and operable from the exterior thereof with the aid of a rack 16b and a manually movable gear segment 16c, or 75 by means of a valve-controlled conduit leading

thereinto, so that under the influence of the high rate of heat interchange secured by the present invention, such rate amounting up to about 1600 cal./m²/hour/° C., rapid steam generation sets in. The steam generated is withdrawn by pipe 17 and conducted to a place of use.

80 A modified construction according to the invention is shown in Figs. 5 to 9. As is shown in Fig. 6, only short connecting pipes are employed for the heat transfer from the hot oil to the water. These pipes consist of cores 19

provided with bores 18, such cores filling the heating tubes 20 to such an extent as to leave only narrow annular spaces 21. These spaces

21 are divided into spiral paths by means of ribs 22 on the inner surfaces of the tubes 20 and are connected on the one hand at the ends of the tubes with the bores 18 of the inserts 19, and on the other hand they are connected at the beginning of the tubes with the collecting chambers 23 for the cooled heating oil. The chambers 23 for the cooled oil form the jacket of the collecting chamber 24 for the uncooled oil.

The walls 25 of the collecting chamber 24 carry the core inserts 19 by means of threaded connections 26, while the jacket walls 27 forming the jacket space 23 for collecting and conducting the cooled oil serve to support the heating tubes 20 in cantilever fashion. The uncooled oil thus

flows first through the bores 18 of the core inserts 19 and thereby, on starting of the oil boiler, 105 reduces the viscosity of the oil films in the narrow spiral passageways 21. After a short time, the hot oil infiltrates into the spaces 21 in the

form of a thin film, after which the method of 110 heat transfer according to the invention comes into operation. The feed water in space 28 outside of the heating tubes 20 is then rapidly heated to boiling and the generated steam is withdrawn

115 through pipe 17.

As is shown in Fig. 5, each of the collecting chambers except the end chambers of the heat exchanger carries heating tubes 20 at both sides thereof, the tubes being so disposed that between

each two chambers a group of heating tubes for 120 each chamber is arranged, and in this way a maximum of heat transfer surface is created.

The heating tubes 20 may be provided upon their external surfaces with any known means 29 for increasing their heat transfer area. The collect- 125

ing chamber 24 for the uncooled oil is connected with a supply tube 30 (see Figs. 7 to 9) while jacket space 23 for the cooled oil is connected with a discharge conduit 31. If a heat exchanger

built in accordance with the invention is em- 130 ployed to utilize the heat abstracted by the cooling oil in the cooling jackets of a combustion

gas turbine by generating steam with such heat, the conduit 30 is connected with discharge connec- 135 tions of the cooling jackets of such combustion turbine, while the conduit 31 leads to the inlet connections of the turbine for the cooled oil.

In the same manner as already described in connection with Fig. 2, the feed water is conducted into the distributing chamber 33 by pipe 140

32 and is conducted from the latter by tubes 34, 35 or 36, 37 distributed along the length of the boiler.

It will be understood that other heat trans- 145 ferring media may be employed besides oil; and that my improved heat exchanger may be em-

ployed for the generation of steam or for the evaporation of liquids by indirect heating.

I claim:

1. A heat exchanger comprising a plurality of 150

- tubes having core inserts therein of such diameter as to form narrow annular spaces between the inner walls of the tubes and the outer surfaces of such cores, means for conducting a substance of poor heat conductivity into said annular spaces, means for conducting a substance of better heat conductivity against the outer walls of the tubes, and tubes not provided with cores for use in starting the apparatus. 5 80
- 10 2. A heat exchanger comprising a plurality of tubes having core inserts therein of such diameter as to form narrow annular spaces between the inner walls of the tubes and the outer surfaces of such cores, means for conducting a substance of poor heat conductivity into said annular spaces, means for conducting a substance of better heat conductivity against the outer walls of the tubes, said exchanger including tubes not provided with cores for use in starting the apparatus, and means 15 90 for closing such last-mentioned tubes against the entry of the substance of poor heat conductivity after the apparatus has been started. 20 95
3. A heat exchanger comprising a plurality of tubes having core inserts therein of such diameter as to form narrow annular spaces between the inner walls of the tubes and the outer surfaces of such cores, means for conducting a substance of poor heat conductivity into said annular spaces, means for conducting a substance of better heat conductivity against the outer walls of the tubes, 25 100
- 30 105
- 35 110
- 40 115
- 45 120
- 50 125
- 55 130
- 60 135
- 65 140
- 70 145
- 75 150
- collecting chambers for the uncooled and the cooled substance of poor heat conductivity, said tubes arranged at both sides of the chambers and connected into groups, a plurality of such groups with their associated chambers being disposed along the length of the heat exchanger one behind the other. 80
4. A heat exchanger comprising a plurality of tubes having hollow core inserts therein of such external diameter as to form narrow annular spaces between the inner walls of the tubes and the outer surfaces of such cores, the outer ends of said cores being open and communicating with said annular spaces, and the outer ends of said tubes being closed, a collecting chamber connected with the inner ends of said cores and communicating with the interior thereof, a conduit for conducting a fluid into said chamber for distribution into said cores and thence into said annular spaces, a second collecting chamber connected with said tubes to support the latter in cantilever fashion and receiving the said fluid after the same has traversed said annular spaces, means for withdrawing the fluid from said second chamber, and means for directing a second fluid 90 95 100 against the outer surfaces of said tubes and into heat exchange relation with the first-mentioned fluid. 100
- HANS HOLZWARTH. 105
